PROGRAM PHASE REVERSER

Jarrett L. Hathaway, Manhasset, N. Y., assignor
to Radio Corporation of America, a corporation
of Delaware

Application October 7, 1937, Serial No. 167,709

10 Claims.

(Cl. 179—1)

This invention relates to systems for controlling the signals derived from a microphone in such manner that the peaks of sound waves which may at times be greater in one direction than in the other are impressed upon the usual amplifiers with suitable phase for obtaining an optimum condition of linear amplification. With system of unsymmetrical limitation, this permits greater undistorted output power.

10 In broadcasting, sound recording, and in various sound pickup systems, including public address systems, it has been found that the electrical circuits involved have greater latitude in one phase than in the reverse, that is, linearity often extends over a greater range in one direction than in the reverse. Therefore, for maximum undistorted speech or program power to be transmitted through such a system, it is essential that the phasing of the voice frequency wave be 20 made such as to place the maximum peaks in the direction of greatest latitude. The human voice often has as much as a two-to-one difference in the peak amplitudes on the positive and negative sides of the sound wave. In normal program work microphones of the so-called "velocity" type are often used, and these microphones are 25 are so disposed with respect to the performers that they pick up sound waves from either one or both sides. Maximum peaks of electromotive force excited by a human voice are of one phase for one side of the microphone and the opposite for the reverse side. In a radio broadcast program it is frequently necessary also to shift the 30 circuits or lines from one microphone to another or to change the location of different microphones. As a result frequent phase reversals occur.

It is an object of my invention to provide a 35 program phase reversing device which will enable a microphone to be utilized in such manner that any amplifier or speech circuit in which non-linearity in one direction is reached at lower amplitude than in the reverse, will have applied thereto a speech wave whose unsymmetric wave peaks are suitably phased for placing these peaks in the direction of greatest latitude.

In the early experimental work that was conducted for the purpose of achieving my objects, it was found necessary to provide means for reversing the phase only during moments of relative silence. Otherwise, the operation of a reversing switch would produce an undesirable audible "plop" or noise. In carrying out my invention, therefore, another object to be attained 55 is to provide means for reversing the phase of

the speech wave without producing any noticeable noise due to circuit switching.

My invention will now be described in greater detail, reference being made to the accompanying drawing, in which the sole figure thereof represents a circuit diagram of a preferred embodiment.

Referring to the drawing, I show an audio-wave phase reversing arrangement in which there is provided an input transformer 5 having two secondary windings of suitable impedance 6 and 7. The secondary winding 6 feeds audio signals to a primary winding of suitable impedance of an output transformer 32. This primary winding has two portions 33 and 34, the respective 10 circuits and connections of which are completed through the back and front contacts of relay-operated switch, presently to be described. Between these contacts there is a movable contact spring 8 connected with one terminal of the secondary winding 6 on transformer 5. The other terminal of this secondary winding is connected to the midpoint between the primary winding portions 33 and 34 on transformer 32. As will be shown hereinafter, the relay 36 can be made 15 to operate during moments of silence for shifting the connection from the lower end of the secondary winding 6, either to the upper portion 33 or the lower portion 34 of the primary on transformer 32, thus reversing the phase of the 20 output.

The secondary winding 7 of transformer 5 is shunted by a potentiometer 9 having an adjustable tap which feeds to the control grid of an amplifier tube 8. The grid of tube 8 has a direct 25 current bias from source 23 through an adjustable tap 40 on the potentiometer 22. The output circuit from this tube includes the primary winding of a transformer 10 which also has two secondary windings 11 and 12. In shunt with the 30 primary of transformer 10 is a potentiometer 13, from which energy may be tapped at a selected voltage for controlling detector tube 14. This energy is directed through a blocking condenser 15, to the grid of said tube 14, which tube is 35 preferably of the grid leak detector type, operating with zero bias at no signal, 16 being the grid leak resistor. The output circuit of the tube 14 includes a relay 28, which is fed with direct current from the source 21. In the absence of signals the tube 14 is conductive and, therefore, permits the relay 28 to be energized. In the 40 presence of signals, however, the grid of the tube 14 is negatively biased to a point where the tube impedance causes the relay 28 to release. 45 50 55

BY

INVENTOR.

JARRETT L. HATHAWAY

H. S. Brown
ATTORNEY

The amber glass being more translucent at low filament temperature of the lamp than the green gives the impression that lamp 36 only is lighted when current passes through both lamps in series; whereas, when the amber lamp 36 is short-circuited and the voltage drop through the lamp 35 is increased, the green lamp only is actually lighted.

Many modifications of my invention may suggest themselves to those skilled in the art in view of the foregoing. The scope of the invention is, therefore, defined by the claims to follow.

What is claimed is:

1. In a circuit arrangement for feeding audio frequency currents of unsymmetric wave characteristics into an amplifier and transducer system having an unsymmetric range of linearity, means operative in dependence upon the sense of an amplitude difference between wave peaks of opposite polarity of said currents for reversing the phase of said currents, and means operative in dependence upon the amplitude level of said currents for fixing the times of such reversals.

2. Apparatus in accordance with claim 1 in which the first said means includes a pair of discharge tubes coupled to the source of said audio frequency currents, said tubes being adapted to rectify opposite half waves of said audio frequency currents.

3. Apparatus in accordance with claim 1 and having a pair of direct current amplifier tubes operative by rectified currents in the first said means, and a relay operative as a function of the total anode current through said amplifier tubes, which current varies in accordance with the disparity between the positive and negative peak levels of said audio frequency currents.

4. Apparatus in accordance with claim 1 in which the first said means includes two rectifiers operating respectively on opposite half waves, an amplifier having at least two triode systems fed from said rectifiers, a relay operable by the output energy from said amplifier, and a phase reversing relay operable by contacts of the first said relay.

5. Apparatus in accordance with claim 1 in which the second said means includes a signal detector and a relay normally energizable in response to the occurrence of a moment of substantially negligible amplitude of said audio frequency currents.

6. Apparatus in accordance with claim 1 and having means operative in dependence upon the occurrence of dissymmetry and an immediately subsequent occurrence of low amplitude level of said audio frequency currents, for reversing the same.

7. Audio wave phase reversing apparatus comprising a pair of electron discharge tubes each having an anode and a cathode, means for feeding a positive half-cycle peak of said audio wave to the anode of one tube and an immediately subsequent half-cycle peak of said audio wave to the anode of the other tube, an amplifier comprising discharge tubes having means for impressing unequal biasing control potentials thereon, said amplifier being responsive to rectified currents from the first said pair of discharge tubes in accordance with the disparity between the positive and negative peaks of said audio wave, a first relay

operable in response to variations in the total anode current of said amplifier tubes, a second relay responsive to variations in the overall amplitude of said audio wave, a third relay of the polarity reversing type having a control circuit through contacts of the first and second relays, and means including said control circuit whereby the third relay is caused to energize only when both first and second relays are energized, and is caused to be de-energized only when the first relay de-energizes and the second relay is simultaneously in an energized state.

8. In a voice frequency circuit arrangement, apparatus for adapting the phase of a biased audio wave to the requirements for obtaining an optimum condition of linear amplification, said apparatus comprising an energy rectifying unit having two electron discharge tubes, means for feeding half-cycle energy peaks of one phase through one of said discharge tubes, means for feeding half-cycle energy peaks of opposite phase through the other of said discharge tubes, a pair of electron discharge amplifier tubes each under control of one of said rectifier tubes respectively, means including unequally biased control grids in said amplifier tubes for effecting non-linear amplification of energy from said rectifying unit, a first relay operable by currents from said amplifier tubes, a second relay operable under control of the amplitude level of currents in said voice frequency circuit, a third relay having phase reversing contacts in said voice frequency circuit, and means for causing the third relay to be operated and to be released under joint control of the first and second relays and only when a moment of silence follows immediately upon a phase reversal of the bias in said audio wave.

9. A reversing switch system for advantageously phasing an unsymmetric current from a given source with respect to an unsymmetric amplifier to which said current is fed, comprising a device for separately rectifying opposite half-cycles of said current, means responsive to amplitude differences between the rectified components so derived for determining the sense of a phase reversal to which said current is to be subjected, switching mechanism comprising a relay having reversible connections between said source and said amplifier, and means operative in response to the reduction of said current to a relatively low amplitude for rendering effective the first said means, said relay being operable when the operation of the second said means immediately follows that of the first said means.

10. The method of reversibly switching the connections of an audio frequency current source to a given amplifier and transducer system having an unsymmetric range of linearity, which comprises deriving separate components of rectified energy from the half-waves of each polarity of said current, obtaining therefrom a differential component the sense of which changes with circumstances, storing said differential component until such time as the audio frequency current is momentarily reduced to an extremely low amplitude level, and then applying said differential component to effect a reversal of said connections.
